UNITED STATES PATENT OFFICE.

THOMAS LAURENT, OF NEW YORK, N. Y., ASSIGNOR TO NATIONAL PNEUMATIC COMPANY, OF NEW YORK, N. Y., A CORPORATION OF WEST VIRGINIA.

FLUID-PRESSURE-ACTUATED MOTOR.

1,412,878.

Specification of Letters Patent. Patented Apr. 18, 1922.

Application filed September 22, 1917. Serial No. 192,650.

To all whom it may concern:

Be it known that I, THOMAS LAURENT, a citizen of the United States, residing at New York, county of New York, State of New York, have made a certain new and useful Invention in Fluid-Pressure-Actuated Motors, of which the following is a specification.

This invention relates to fluid pressure actuated motors.

The object of the invention is to provide a fluid pressure actuated motor of standard construction with a type of cushioning connection associated therewith, and to provide means for insuring the cushioning action of said connections.

A further object of the invention is to insure a proper sequence of operation of the controlling means of the motor.

20 Further objects of the invention will appear more fully hereinafter.

The invention consists substantially in the construction, combination, location, and relative arrangement of parts, all as will be 25 more fully hereinafter set forth, as shown by the accompanying drawing, and finally pointed out in the appended claims.

Referring to the drawing:

Fig. 1 is a view in elevation of a standard 30 type of fluid pressure motor with diagrammatic piping system and valve control of the same.

Figs. 2 and 3 are views of the valve and valve seat for various positions of the valve 35 on its seat.

Fig. 4 is a sectional view taken on the line 4-4 of Fig. 3 and looking in the direction of the arrows.

Fig. 5 is a bottom face view of the valve 40 employed in accordance with my invention;

Fig. 6 is a sectional view taken on the line 5-5, Fig. 5, and looking in the direction of the arrows.

The same part is designated by the same 45 reference numeral wherever it occurs throughout the several views.

In pneumatic engines or motors there are in practice three different types. In all types it is necessary to have some automatic 50 means of cushioning or retarding the motion of the engine towards the end of its stroke. In the one type, which I will call the first type, the pressure that has operated the engine in one direction is not liberated at the

end of the stroke, but is retained until the 55 moment the engine is reversed when part of this pressure is exhausted, a sufficient portion being retained however to cushion the final motion of the engine.

In the second type, the pressure is automatically exhausted at the end of the travel 60 of the engine, and when the engine is reversed the action is obtained by compressing the free air in that end of the engine. Of necessity the relative arrangement and size 65 of the exhaust ports that are suitable for the first type would be unsuitable for the second type as the pressure of the air on which the cushioning feature depends is much lower in the second type than in the 70 first type.

The third type of engine employs exterior auxiliary means for cushioning the engine at the limits of its movements. This invention has reference to the first type of 75 engine above described, and to that form of the same in which the controlling valve is manually operated. When the valve is operated electrically or pneumatically it is moved instantly from one desired position 80 to another, but when manually operated it is possible for it to be moved slowly and gradually and therefore conditions may arise due to the position of the valve intermediate its proper extreme positions that 85 could not arise with a power operated valve.

In ordinary practice the valve is moved from one extreme position to the other, and heretofore, therefore, no exact detail has been followed in regard to the sequence with 90 which the various ports were opened or closed, it being deemed sufficient in one extreme to have one piston or cylinder end open to pressure and closed to exhaust and the other piston or cylinder end open to 95 exhaust, usually through a more or less restrictive opening, and closed to pressure.

In practice, however, as for instance, when used to operate doors on street cars, it has been found that sometimes the conductor will "creep" his control handle little by little from one extreme position to the other with the result that the retarding pressure in either end of the cylinder is allowed to escape before the door starts to move, and 100 the size of the cushioning ports being suited to an engine that cushions on considerable pressure, there would not remain enough

pressure in the exhaust end of the engine to properly cushion its motion, and the door would slam open or shut. It is among the special purposes of my present invention to so relate the position of the ports that in moving the valve from one extreme to the other, the following sequence is followed:—

1. The end of the cylinder that has been open to exhaust has the exhaust cut off while 10 the other end of the engine still remains open to pressure.

2. The end formerly open to exhaust then becomes opened to pressure. The other end still remaining open to pressure. This leaves 15 both ends closed to exhaust and both ends open to pressure. This is the central or neutral position of the valve.

3. The end thus far continuously open to pressure is then closed to pressure.

20 4. The end which was originally open to pressure and which became closed in its third position now becomes open to exhaust.

It will be seen, therefore, that at no position of the valve can the pressure blow 25 through to exhaust, and that at the moment one end of the engine is commencing to be open to exhaust, the other end has already become open to pressure, so that the engine instantly responds to the pressure 30 sure acting against the lessened pressure at the exhausting end, and the proper action of the cushioning effect is obtained.

Referring to the drawing wherein I show one embodiment of my invention, I designate 35 the fluid pressure actuated motor of the usual or standard construction. My invention is not concerned in the specific type of motor employed, but I show a standard type which consists of cylinders 2, 3, 40 in which operate the pistons 4, 5, which pistons are connected by rack bar 6, which rack bar meshes with the gear segment 7 which is connected to the arm 8, which in turn controls the door or the moving body. 45 The respective ends of the cylinders 2, 3, are connected by pipes 9, 10, to the ports 11, 12, respectively of the valve seat 13. Ports 14 and 15 of the valve seat 13 lead into the cylinders 2, 3, through pipes 16 50 and 17 respectively, and terminate in ports 18 and 19, which are uncovered by pistons 4, 5, at the limit of their travel in cylinders 2, 3. Fluid pressure is supplied to the valve and valve seat through port 19 and the port 55 20 of the valve seat leads to exhaust. The valve seat thus far described is of the usual and standard type, and the valve 30 which operates on the same is likewise of the usual standard type provided with the 60 usual passages 21 and 22 in its seating face, the passage 21 controlling the exhaust and the passage 22 controlling the supply. The passage 21 is provided with auxiliary passages of smaller relative size 24, 25, which 65 are provided at their ends with relatively

small ports 26 and 27, which ports are adapted to communicate with ports 11 and 12 respectively when the valve 30 is turned in one direction or another to its extreme position to operate the motor in one direction or the other. 70

The operation of the system is obvious. With the valve in the position shown in Fig. 3, which is its central or neutral position, it will be seen that both ends of the cylinder 75 are closed to exhaust inasmuch as none of the ports 14, 15, 11, or 12, are in communication with the exhaust port 20, the fluid pressure is allowed to flow from port 19, passage 22, through port pipes 9 and 10 to 80 both ends of the cylinder. When the valve is shifted towards the position shown in Fig. 2 port 12 becomes closed to the supply and port 11 remains open thereto so that with the pressure removed from the 85 piston 5 the engine starts its movement to move the pistons 4 and 5 towards the right. When it has reached its extreme position, namely, that illustrated in Fig. 2, it will be seen that the port 15 has become opened to 90 exhaust through passage 21, and that there is a free exhaust from the cylinder 3 through pipe 17 to exhaust until the piston 5 closes the port 19. The restricted port 27 however is now in communication 95 with port 12 and pipe 10 to the end of the cylinder 3 so that the remaining movement of the motor is against the restricted exhaust of the fluid pressure which remains in the cylinder thereby insuring the proper 100 cushioning action.

To operate the engine in the other direction from this position of the valve it will be seen that the valve will have to pass through neutral position and will have to 105 insure a supply of pressure to the exhaust through both ends of the cylinder before either end can be exhausted thereby rendering the manual operation of this type of fluid pressure motor or engine a proof 110 against intentional or accidental misuse to prevent the proper functioning of the cushioning means employed in connection therewith.

Having now set forth the object and nature of my invention, what I claim as new and useful, and of my own invention, and desire to secure by Letters Patent, is,—

1. The combination with a fluid pressure motor comprising cylinders, pistons operating in said cylinders, a pipe line leading to the end of each of said cylinders, a valve controlling said pipe line, a source of fluid pressure supply, and an exhaust port controlled by said valve, means for establishing communication between each of said pipe lines with either said exhaust port or said source of fluid pressure supply, and means for preventing the admission of fluid pressure from said source to one of said 115 120 125 130

cylinders until said cylinder has been closed to exhaust, and for admitting pressure to said cylinder before the supply of fluid pressure to the other cylinder has been cut off, and in the initial operation from extreme position whereby a cushioning action is secured.

2. The combination with a fluid pressure motor comprising cylinders, pistons operating in said cylinders, a pipe line leading to the end of each of said cylinders, a valve controlling said pipe line, a source of fluid pressure supply, and an exhaust port controlled by said valve, means for establishing communication between each of said pipe lines with either said exhaust port or said source of fluid pressure supply, means for normally admitting fluid pressure to both of said pipe lines and prior to closing one of said cylinders to exhaust in initiating the operation of the motor from its extreme position whereby a cushioning action is secured.

3. The combination with a fluid pressure motor comprising cylinders, pistons operating in said cylinders, a pipe line leading to the end of each of said cylinders, a valve controlling said pipe line, a source of fluid pressure supply, and an exhaust port controlled by said valve, means for establishing communication between each of said pipe lines with either said exhaust port or said source of fluid pressure supply, means for normally admitting fluid pressure to both of said pipe lines and for closing said cylinder to exhaust when said valve is in its central or neutral position, and means when said valve is moved towards operative position for shutting off the supply of pressure from one of said cylinders before opening said cylinder to exhaust in initiating the operation of the motor from its extreme limit of action in either direction.

4. In a fluid pressure actuated motor, comprising cylinders, pistons operating in said cylinders, and means for supplying fluid pressure to and the exhaust thereof from said cylinders, ports for controlling the said supply and exhaust of fluid pressure to and from said cylinders, a manually operated valve for controlling said ports, and means for supplying fluid pressure to one of said cylinders prior to the movement of the piston therein in exhausting direction to cushion the movements of said piston irrespective of the position of the valve when moved towards an operative position.

5. In a fluid pressure actuated motor, comprising cylinders, pistons operating in said cylinders, means for supplying fluid pressure to and the exhaust thereof from said cylinders, ports controlling the said supply and exhaust of fluid pressure to and from said cylinders, a manually operated valve for controlling said ports, and means for supplying fluid pressure to one of said cylinders prior to the initial movement of the piston therein in exhausting direction to cushion the movements of said piston irrespective of the length of time consumed in moving the valve to complete operative position.

6. In a fluid pressure actuated motor, comprising cylinders, pistons operating in said cylinders, and means for supplying fluid pressure to and the exhaust thereof from said cylinders, a valve for controlling said fluid pressure comprising means for supplying fluid pressure to one cylinder, and opening the second cylinder to exhaust when the valve is at one limit of its movement, and means controlled by the movement of the valve towards its other limit of movement for successively closing said second cylinder to exhaust, then supplying fluid pressure to said second cylinder, then shutting off the supply of fluid pressure to said first cylinder, and finally opening said first cylinder to exhaust whereby a cushioning action is secured.

7. In a fluid pressure actuated motor, comprising cylinders, pistons operating in said cylinders, and means for supplying fluid pressure to and the exhaust thereof from said cylinders, a valve for controlling said fluid pressure comprising means for supplying fluid pressure to one cylinder, and opening the second cylinder to exhaust when the valve is at one limit of its movement, and means controlled by the movement of the valve towards its other limit of movement and irrespective of the speed of movement thereof for successively closing said second cylinder to exhaust, then supplying fluid pressure to said second cylinder, then shutting off the supply of fluid pressure to said first cylinder, and finally opening said first cylinder to exhaust whereby a cushioning action is secured.

In testimony whereof I have hereunto set my hand on this 20th day of September A. D., 1917.

THOMAS LAURENT.
